CLAIM

The ornamental design for a combined decorative light track and adjustable light fixture holder therefore, as shown and described.

DESCRIPTION

FIG. 1 is a perspective view of the combined decorative light track and adjustable light fixture holder therefore embodying the design of the present invention;

FIG. 2 is a front elevational view thereof, the rear being a mirror image of the front shown in FIG. 2;

FIG. 3 is a side elevational view thereof;

FIG. 4 is a opposite side elevational view thereof;

FIG. 5 is a top plan view thereof; and,

FIG. 6 is a bottom view thereof.

FIG. 3.

FIG. 4.

FIG. 6.

FIG. 5.
